UNITED STATES PATENT OFFICE.

WILHELM ZIERENBERG, OF CASSEL, GERMANY.

BURGLARPROOF PICTURE FRAME.

Application filed February 25, 1927, Serial No. 170,852, and in Germany March 2, 1926.

This invention relates to improved means for guarding pictures, particularly such of high value, against their being cut out of their frames by burglars, and it consists in placing directly behind the picture cloth a layer resisting to the action of cutting tools and preventing a smooth and rectilinear cutting, said layer consisting of corrugated hard sheet-metal, of which the corrugations are obliquely directed.

In most cases, it suffices to arrange said layer of a certain breadth at the back of the picture along the rear stretching frame of the picture cloth, where the pictures are generally cut out of their frames by burglars.

It is known that the cutting work by burglars must be quickly done during the short absence of the attendants in a museum or the like, and this quick work is quite impossible with the layer placed behind the picture, while furthermore a smooth and rectilinear cutting required for maintaining the value of the cut-out picture is also made impossible.

The improved guard can be easily provided on any existing pictures without high costs, and it is not visible from outside.

The accompanying drawing illustrates by way of example how the invention can be put into practice: Fig. 1 is a front view of a picture in its frame, while Fig. 2 is a section on the line A—B of Fig. 1.

Directly behind the picture cloth *a* a layer *b* of corrugated sheet-metal, preferably zinc, is placed along the rear stretching frame *c* of the picture cloth, the corrugations of the sheet-metal layer *b* running in oblique directions whereby the guarding action of the same is considerably increased.

What I claim, is:

The combination with a picture frame, of a layer placed directly behind the place to be assumed by a picture cloth in said frame and resisting to the action of cutting tools while preventing a smooth and rectilinear cutting, said layer consisting of corrugated hard sheet-metal of which the corrugations are obliquely directed.

In testimony whereof I have hereunto set my hand.

WILHELM ZIERENBERG.
